UNITED STATES PATENT OFFICE.

HERMANN SCHULTZ, OF BERLIN, LANKWITZ, GERMANY, ASSIGNOR TO METAL & THERMIT CORPORATION, OF CHROME, NEW JERSEY, A CORPORATION OF NEW JERSEY.

CRUCIBLE FOR ALUMINO-THERMIC PROCESSES.

Application filed January 22, 1924. Serial No. 687,762.

To all whom it may concern:

Be it known that I, HERMANN SCHULTZ, a citizen of Germany, residing at Berlin, Lankwitz, Germany, and State of Prussia, have invented certain new and useful Improvements in Crucibles for Alumino-Thermic Processes, of which the following is a specification.

My invention relates to certain improvements in crucibles for alumino-thermic processes.

The crucibles generally used for alumino-thermic processes consists of a shell made of thin sheet iron having a thick lining of refractory material, such as burned magnesia or the like. These crucibles have a short life because their inner lining is worn out by the excessively high temperature of the molten mass.

My invention has for its object the provision of a crucible for alumino-thermic processes which is of maximum durability. To this end the crucible consists in the main of a material of high conductivity for heat, such as copper, bronze, steel, cast iron and the like, and its wall is of such thickness that it has a high capacity for heat. The effect is the following:

The liquid mass which is produced by the alumino-thermic processes consists of a metal and a slag (corundum). Owing to its lower specific gravity the slag ascends from all parts to the top of the molten mass and on the way covers the inner surface of the crucible, where it is partly solidified into an adherent thin lining. The remelting of the latter is prevented by the great conductivity and capacity for heat possessed by the crucible, so that this lining protects the metallic wall against corrosion by the molten slag and the alumino-genetic metal during the whole process.

In designing a crucible of the character indicated, it is necessary to provide sufficient thickness of the metal walls as to enable the heat of the reaction to be conducted away from the inner surface of the wall rapidly enough to prevent such inner surface being actually melted and, with such a crucible, there is absolutely no need for a lining of any kind, except the slag lining that is formed during the reaction. The maintenance of a relatively cool inner surface of the crucible wall, due to the dissipation of

the heat by the metal wall will immediately effect a chilling of the thin layer of slag deposited on the wall, said slag layer setting up into a pasty condition and preventing further contact between the highly molten metal and the inner wall of the crucible. Although this slag coating is usually very thin, probably in the neighborhood of $\frac{1}{16}$ of an inch, nevertheless it is seemingly a sufficiently poor conductor to prevent the melting of the inner wall of the crucible by the heat generated in the reaction mass within the crucible. No hard and fast rule to determine the thickness of the crucible walls can be made, but a more or less general rule is that the thickness of the crucible walls is such as to provide sufficient metal to conduct away enough heat to prevent melting or fusion of the inner surface of the wall through the nonconducting slag coating formed in the reaction and deposited on said surface. As a general proposition, it is desirable to make the walls of the crucible a little thicker than the application of this general rule would require.

It is not necessary to remove this lining at the beginning of a new process, consequently the crucible may be used continually. The alumino-thermic mixture with which the crucible is refilled will then absorb the heat accumulated in the thick wall.

The crucible may also be provided in advance with a thin lining of refractory material all over the whole of its inner surface or only in its lower part, for instance up to the level of the liquid metal.

In the drawing, Figs. 1 and 2 are vertical sections through crucibles embodying my invention. Similar letters of reference designate corresponding parts in both the figures. A represents the metallic wall of the crucible, B a liner of burned magnesia in the discharge outlet, made interchangeable to provide for wear and tear, and C a thin lining of refractory material in the lower part of the inner metallic wall.

What I claim is:

1. A receptacle for use in effecting the reduction of metals by means of metallic reducing agents comprising a metal crucible of sufficient wall thickness to chill on its inner surface a thin layer of slag produced by the reaction.

2. A receptacle for use in effecting exo-

thermic reactions comprising an initially unlined metal crucible of sufficient wall thickness to chill on its inner surface a thin layer of slag produced by the reaction.

5 3. A receptacle for use in effecting exothermic reactions comprising a metallic crucible of sufficient wall thickness to convey away sufficient of the heat of reaction to prevent fusion of its inner surface, said crucible

having a lining of slag produced by the re- 10 action.

In testimony whereof I affix my signature in presence of two witnesses.

HERMANN SCHULTZ.

Witnesses:

WLAD ENDERS,
ROGER S. AUSPACE.
